3 Claims

ABSTRACT OF THE DISCLOSURE

New indenoimidazoles useful in the inhibition of phenylethanolamine-N-methyl transferase.

This invention relates to new chemical compounds. More specifically, this invention relates to new indenoimidazoles. Still more specifically, this invention relates to compounds having the following general formula:

wherein R₁ is hydrogen, methylthio or

and R₂, R₃, R₄, and R₅ each may be hydrogen, trifluoromethyl, halo or nitro.

A final step in epinephrine biosynthesis is the transfer of a methyl group from S-adenosylmethionine to the amine nitrogen of norepinephrine. This step is catalyzed by phenylethanolamine-N-methyl transferase. This invention further relates to a method of inhibiting the formation of phenylethanolamine-N-methyl transferase utilizing the compounds of this invention, thereby resulting in a decrease in the formation of adrenal epinephrine.

These compounds have clinical utility in situations where there is a selective overproduction of adrenal epinephrine such as in the treatment of narcotic addiction, for example the management and control of morphine withdrawal, the treatment of various emotional states, for example anticipatory, painful and anxiety states in normal and psychiatric subjects, in particular for the treatment of anxiety neurosis, and the prophylactic control of cardiovascular disorders characterized by increased heart rate and cardiac output, management of heart failure, cardiac shock or other situations in which stress exerts pressure upon cardiac performance, as, for example, the management of myocardial infarctions.

The compounds of this invention also are useful as fungicides and coccidiostats and may be used to treat diseases and conditions characterized by the presence of coccidia or fungi.

The compounds of this invention wherein R₁ is a phenyl group are prepared by reacting the appropriate indanone with a benzimidine derivative in the presence of ammonia. When R₁ is hydrogen or methylthio, the appropriate indanone is converted to its 2-amino derivative which is reacted with potassium thiocyanate to form the corresponding indenoimidazole.

A preferred embodiment of this invention is a method of inhibiting phenylethanolamine-N-methyl transferase which comprises the administration to a patient (animal or human) of a therapeutically effective amount of the compounds of the above formula. In general the daily dose can be from 0.05 mg./kg. to 150 mg./kg. per day and preferably from 1 mg./kg. to 100 mg./kg. per day, bear-

2

ing in mind, of course, that in selecting the appropriate dosage in any specific case, consideration must be given to the patient's weight, general health, metabolism, age and other factors which influence response to the drug.

Another embodiment of this invention is the provision of pharmaceutical compositions in dosage unit form which comprise from about 1 mg. to 500 mg. of a compound of the above formula.

The pharmaceutical compositions may be in a form suitable for oral use, for example, as tablets, aqueous or oily suspensions, dispersible powders or granules, emulsions, hard or soft capsules, or syrups or elixers. Compositions intended for oral use may be prepared according to any method known to the art for the manufacture of pharmaceutical compositions, and such compositions may contain one or more agents selected from the group consisting of sweetening agents, flavoring agents, coloring agents and preserving agents in order to provide a pharmaceutically elegant and palatable preparation. Tablets contain the active benzimidazole ingredient in admixture with non-toxic pharmaceutically acceptable excipients which are suitable for manufacture of tablets. These excipients may be, for example, inert diluents, for example calcium carbonate, sodium carbonate, lactose, calcium phosphate or sodium phosphate; granulating and disintegrating agents, for example maize starch, or alginic acid; binding agents, such as starch, gelatin, or acacia, and lubricating agents, for example magnesium stearate, stearic acid or talc. The tablets may be uncoated or they may be coated by known techniques to delay disintegration and absorption in the gastrointestinal tract and thereby provide a sustained action over a longer period.

Formulations for oral use may also be presented as hard gelatin capsules wherein the active ingredient is mixed with an inert solid diluent, for example calcium carbonate, calcium phosphate or kaolin, or as soft gelatin capsules wherein the active ingredient is mixed with an oil medium, for example arachis oil, liquid paraffin or olive oil.

Aqueous suspensions contain the active benzimidazole in admixture with excipients suitable for the manufacture of aqueous suspensions. Such excipients are suspending agents, for example sodium carboxymethylcellulose, methylcellulose, hydroxypropylmethylcellulose, sodium alginate, polyvinylpyrrolidone, gum tragacanth and gum acacia; dispersing or wetting agents may be a naturally occurring phosphatide, for example lecithin, or condensation products of an alkylene oxide with fatty acids, for example polyoxyethylene stearate, or condensation products of ethylene oxide with long chain aliphatic alcohols, for example heptadecaethylenoxy-cetanol, or condensation products of ethylene oxide with partial esters derived from fatty acids and a hexitol, for example polyoxyethylene sorbitol mono-oleate, or condensation products of ethylene oxide with partial esters derived from fatty acids and hexitol anhydrides, for example polyoxyethylene sorbitan mono-oleate. The said aqueous suspensions may also contain one or more preservatives, for example, ethyl, or n-propyl, p-hydroxy benzoate, one or more coloring agents, one or more flavoring agents and one or more sweetening agents, such as sucrose, saccharin, or sodium or calcium cyclamate.

Oily suspensions may be formulated by suspending the active ingredient in a vegetable oil, for example arachis oil, olive oil, sesame oil or coconut oil, or in a mineral oil such as liquid paraffin. The oily suspensions may contain a thickening agent, for example beeswax, hard paraffin or cetyl alcohol. Sweetening agents, such as those set forth above, and flavoring agents may be added to provide a palatable oral preparation. These compositions may be preserved by the addition of an anti-oxidant such as ascorbic acid.

Dispersible powders and granules suitable for preparation of an aqueous suspension by the addition of water provide the active ingredient in admixture with a dispersing or wetting agent, suspending agent and one or more preservatives. Suitable dispersing or wetting agents and suspending agents are exemplified by those already mentioned above. Additional excipients, for example sweetening, flavoring and coloring agents, may also be present.

The pharmaceutical compositions of the invention may also be in the form of oil-in-water emulsions. The oily phase may be a vegetable oil, for example olive oil or arachis oils, or a mineral oil, for example liquid paraffin or mixtures of these. Suitable emulsifying agents may be naturally occurring gums, for example gum acacia or gum tragacanth, naturally occurring phosphatides, for example soya bean lecithin, and esters of partial esters derived from fatty acids and hexitol anhydrides, for example sorbitan mono-oleate, and condensation products of the said partial esters with ethylene oxide, for example polyoxyethylene sorbitan mono-oleate. The emulsions may also contain sweetening and flavoring agents.

Syrups and elixirs may be formulated with sweetening agents, for example glycerol, sorbitol or sucrose. Such formulations may also contain a demulcent, a preservative and flavoring and coloring agents. The pharmaceutical compositions may be in the form of a sterile injectable preparation, for example as a sterile injectable aqueous suspension in a non-toxic parenterally-acceptable diluent or solvent, for example as a solution in 1:3-butane diol.

The pharmaceutical compositions may be tableted or otherwise formulated so that for every 100 parts by weight of the composition there are present between 5 and 95 parts by weight of the active ingredient. The dosage unit form will generally contain between about 100 mg. and about 500 mg. of the active ingredient of the formula stated above.

From the foregoing formulation discussion it is apparent that the compositions of this invention can be administered orally or parenterally. The term parenteral as used herein includes subcutaneous injection, intravenous, intramuscular, or intrasternal injection or infusion techniques.

The following examples are presented to further illustrate the invention.

EXAMPLE 1

(A) 4-trifluoromethylbenzimidic acid ethyl ester hydrochloride

A mixture of 17.1 g. of p-trifluoromethylbenzonitrile and 25 ml. of absolute ethyl alcohol is stirred and cooled with an ice bath before 75 ml. of ethyl alcohol which was cooled to 0° C. and saturated with hydrogen chloride is added. After four days at 5° C., the solution is concentrated in vacuo to a slush, and ethyl ester is added to precipitate 4-trifluoromethylbenzimidic acid ethyl ester hydrochloride, M.P. 185-186° C.

(B) 4-trifluoromethylbenzimidine hydrochloride

A 7.5 g. portion of 4-trifluoromethylbenzimidic acid ethyl ester hydrochloride is dissolved in 40 ml. of absolute ethyl alcohol, and a 5% solution of ammonia-ethyl alcohol is added in 1 ml. portions with stirring until the odor of ammonia persists. After standing two days, the solution is concentrated to a solid which is washed well with ethyl ester to give 4-trifluoromethylbenzimidine hydrochloride, which is used without further purification.

(C) 2-(4-trifluoromethylphenyl)-1,4(8)-dihydroindeno[1,2d]-imidazole

A mixture of 3.24 g. of 2-bromo-1-indanone in 30 ml. of chloroform and 3.30 g. of 4-trifluoromethylbenzimidine hydrochloride in 10 ml. of water is stirred vigorously, and 1.8 g. of potassium hydroxide in 10 ml. of water is added. The mixture is stirred and refluxed for 3 hours before the resultant precipitate is collected and

70
75

washed with water and chloroform to give 0.80 g. of intermediate hydroxy compound. A 0.70 g. portion of this intermediate is refluxed 10 minutes in 7 ml. of acetic acid. The acetic acid is removed in vacuo and the residue extracted with 10 ml. of ethyl ester. The ethyl ester extract is concentrated to crude product, which is recrystallized four times from methyl alcohol to give product, M.P. 206-211° C.

Using the same reaction conditions and techniques, 4-chloromethylbenzylamidine and 4-nitromethylbenzimidine are reacted with 2-bromo-1-indanone to produce 2-(4-chloromethylphenyl)-1,4(8)-dihydroindeno[1,2d]-imidazole and 2-(4-nitromethylphenyl)-1,4(8)-dihydroindeno[1,2d]-imidazole.

EXAMPLE 2

Indeno[1,2d]-imidazole

A 1.0 g. portion of 2-mercaptoindeno[1,2d]-imidazole and 7-8 g. of Raney nickel are stirred and refluxed in 30 ml. of ethyl alcohol for one hour. While still hot the mixture is filtered to remove the Raney nickel, which is washed with 3 X 10 ml. of ethyl alcohol. The filtrate and washings are concentrated to yield a pale green cure product, which is purified by sublimation, M.P. 168-172° C.

EXAMPLE 3

2-methylthioindeno[1,2d]-imidazole

To a slurry of 1.88 g. of 2-mercaptoindeno[1,2d]-imidazole in 50 ml. of tetrahydrofuran is added 0.70 ml. of iodomethane. After 16 hours of stirring, the precipitate is collected and stirred with excess 1 N sodium hydroxide. Collection of the precipitate yields product, M.P. 166-168° C.

EXAMPLE 4

(A) 6-chloro-1-indanone

A mixture of 35 g. of p-chlorohydrocinnamic acid and 414 g. of polyphosphoric acid is heated on a steam bath for one-half hour. Dilution with 3 liters of water gives a precipitate which is dissolved in ethyl ester. The ethyl ester solution is washed with sodium bicarbonate, steam distilled, and the steam distilled material recrystallized from ethyl alcohol to give product, M.P. 70-73° C.

(B) 6-chloro-2-isonitroso-1-indanone

A solution of 5.7 g. of 6-chloro-1-indanone in 60 ml. of benzene is stirred, and hydrogen chloride gas is bubbled in as 4.8 g. of t-amylnitrite is added dropwise over a 50 period of 15 minutes. Addition of hydrogen chloride is continued 20 minutes longer. The mixture is stirred 15 hours before product is collected, M.P. 200-204° dec.

Using the same reaction conditions and techniques, 5-bromo-1-indanone, 6-bromo-1-indanone, 5-chloro-1-indanone, 5-fluoro-1-indanone, 6-fluoro-1-indanone and 5-nitro-1-indanone are reacted with t-amylnitrite to produce 5-bromo-2-isnitroso-1-indanone, 6-bromo-2-isnitroso-1-indanone, 5-chloro-2-isnitroso-1-indanone, 5-fluoro-2-isnitroso-1-indanone, 6-fluoro-2-isnitroso-1-indanone and 5-nitro-2-isnitroso-1-indanone, respectively.

(C) 2-amino-5-chloro-1-indanone

To a stirred mixture of 9.13 g. of stannous chloride dihydrate in 13 ml. of concentrated hydrogen chloride is added portionwise 3.6 g. of 6-chloro-2-isnitroso-1-indanone over a period of one and one-half hours. The temperature is maintained at less than 40° C. with intermittent cooling. After stirring for one-half hour at room temperature and one-half hour at 95° C., the mixture is cooled and 500 ml. of water is added. The mixture is stirred and hydrogen sulfide is bubbled in until no further precipitate is obtained. Solids are removed by filtration, and concentration of the filtrate gives crude product, which is purified and recrystallized from methyl alcohol-ethyl ester to yield product, M.P. 195-200° dec.

(D) 5(7)-chloro-2-mercapto-1,4(8)-dihydroindeno-[1,2d]-imidazole

A mixture of 1.44 g. of 2-amino-5-chloro-1-indanone and 0.675 g. of potassium thiocyanate are refluxed for 15 minutes in 45 ml. of glacial acetic acid. After cooling, crude product is collected on a filter and is used without further purification.

(E) 5(7)-chloro-1,4(8)-dihydroindeno-[1,2d]-imidazole

A 310 mg. portion of crude 5(7)-chloro-2-mercapto-1,4(8)-dihydroindeno-[1,2d]-imidazole is treated with Raney nickel according to the procedure of Example 2 to give crude product which is purified by preparative TLC (10% methyl alcohol-chloroform on silica gel G) followed by trituration with ether to yield product, M.P. 198-201.5° C.

The indanones produced by the procedure of Example 4(B) are reacted by the procedures of Examples 4(C), 4(D) and 4(E) to produce the corresponding imidazoles.

EXAMPLE 5

5(7)-chloro-2-methylthio-1,4(8)-dihydroindeno-[1,2d]-imidazole

A 0.31 g. portion of crude 5(7)-chloro-2-mercapto-1,4(8)-dihydroindeno-[1,2d]-imidazole is treated with iodomethane as described in Example 3 to yield product, M.P. 219-223° C.

EXAMPLE 6

A mixture of 250 parts of 2-(4-trifluoromethylphenyl)-1,4(8)-dihydroindeno-[1,2d]-imidazole and 25 parts of lactose is granulated with suitable water, and to this is added 100 parts of maize starch. The mass is passed through a 16-mesh screen. The granules are dried at a temperature below 60° C. The dry granules are passed through a 16-mesh screen, and mixed with 3.8 parts of magnesium stearate. They are then compressed into tablets suitable for oral administration.

EXAMPLE 7

A mixture of 50 parts of indeno-[1,2d]-imidazole, 3 parts of the calcium salt of lignin sulfonic acid, and 237 parts of water is ball-milled until the size of substantially all of the particles of benzyl ethyl sulfoxide is less than 10 microns. The suspension is diluted with a solution containing 3 parts of sodium carboxymethylcellulose and 0.9 part of the butyl ester of p-hydroxybenzoic acid in 300 parts of water. There is thus obtained an aqueous suspension suitable for oral administration for therapeutic purposes.

EXAMPLE 8

A mixture of 250 parts of 2-amino-5-chloro-1-indanone, 200 parts of maize starch and 30 parts of alginic acid is

mixed with a sufficient quantity of a 10% aqueous paste of maize starch, and granulated. The granules are dried in a current of warm air and the dry granules are then passed through a 16-mesh screen, mixed with 6 parts of magnesium stearate and compressed into tablet form to obtain tablets suitable for oral administration.

EXAMPLE 9

A mixture of 500 parts of 5(7)-chloro-1,4(8)-dihydroindeno-[1,2d]-imidazole, 60 parts of maize starch and 20 parts of gum acacia is granulated with a sufficient quantity of water. The mass is passed through a 12-mesh screen and the granules are passed through a 16-mesh screen, mixed with 5 parts of magnesium stearate and compressed into tablet form suitable for oral administration.

What is claimed is:

1. A compound of the formula

2. A compound of the formula

35 wherein R₂ is halo.

3. A compound of the formula

40 wherein R₂ is halo.
